Des. 184,445
Patented Feb. 17, 1959

184,445

APPLICATOR FOR APPLYING TREATING MATERIAL TO THE HAIR

Louis L. Lerner, Chicago, Ill., assignor to The Gillette
Company, Boston, Mass., a corporation of Delaware

Application May 6, 1957, Serial No. 46,026

Term of patent 14 years

(Cl. D86—10)

Fig. 1 is a perspective view of an applicator showing my new design, the dotted lines indicating a container on which the applicator is adapted to be mounted;

Fig. 2 is a view in side elevation;

Fig. 3 is a view in end elevation; and

Fig. 4 is a top plan view.

I claim:

The ornamental design for an applicator for applying treating material to the hair, as shown and described.
